UNITED STATES PATENT OFFICE.

FRANCIS M. LEWIS, OF SEATTLE, WASHINGTON, ASSIGNOR TO AUGUSTUS J. SORGE,
OF SEATTLE, WASHINGTON.

AMALGAMATOR.

1,354,497.

Specification of Letters Patent.

Patented Oct. 5, 1920.

Application filed September 30, 1919. Serial No. 327,468.

To all whom it may concern:

Be it known that I, FRANCIS M. LEWIS, a citizen of the United States, residing at Seattle, in the county of King and State 5 of Washington, have invented certain new and useful Improvements in Amalgamators, of which the following is a specification.

This invention relates to means for recovering from water or semi-liquid material 10 gold and other valuable products, and the object of the invention is to provide means of novel construction whereby the recovery of the valuable elements will be accomplished automatically in a continuously operating process. The invention is illustrated in the accompanying drawings and 15 consists in certain novel features which will be particularly pointed out in the claims following a detailed description.

20 In the drawings—

Figure 1 is an elevation of an amalgamator embodying my improvements, parts being broken away and parts in section;

25 Fig. 2 is an end elevation with parts broken away and in section;

Fig. 3 is a detail perspective view of a head block;

Fig. 4 is a detail perspective view of a partition.

30 In carrying out the invention, I employ a tank consisting of end plates 1 which are held against separation by transverse bars or rods 2 inserted therethrough at intervals and having threaded ends upon which 35 clamping nuts 3 are mounted. Between the said side plates, a bottom plate 4 is held, the said bottom plate being of any suitable material and so shaped that it will clear the securing rods 2 as will be readily understood. This bottom plate is also shaped to 40 provide a rear amalgamating chamber 5 and a forward receiving chamber 6, as clearly shown in Fig. 2. An amalgamating plate 7 is fitted within the amalgamating chamber 5 and extends from the front wall of the same over an intermediate bridging portion 8 of the bottom plate 4, this amalgamating plate being so shaped as to fit closely to the front and rear walls of the amalgamating chamber and forming a complete 45 lining for the same. The concentrates or material to be treated in the amalgamator is fed into the amalgamating chamber through a hopper 9 which is supported upon the tank at or near the rear side of the

same and is held against displacement by rods 10 fitted in eyes 11 upon the tank and the hopper, as clearly shown, it being noted that upper and lower eyes are provided upon the ends of the hopper so that one or 60 more brace rods may be used as may be deemed desirable. To provide for an even distribution of the concentrates or other material and to permit the use of relatively small amalgamating plates which may be 65 conveniently handled, the amalgamating chamber is preferably divided into a plurality of compartments by partitions 12 disposed transversely of the chamber or longitudinally of the amalgamator and these partitions are provided intermediate their front and rear edges with upwardly projecting tongues 13 through which a clamping rod 14 may pass, the said rod also passing through the ends of the tank so as to aid 70 in securing the several parts together. The provision of the upwardly projecting tongue 13 also produces a shoulder 15 in rear of the tongue upon which the lower end of the hopper may rest. Between the partitions, I provide head blocks 16 which in 75 their upper portions are equal in thickness to the width of the tongues 13 of the partitions so that the front and rear sides of the head blocks will be flush with the front and rear edges of said tongues and the head blocks may be held in place by the same rods 14 which secure the partitions. Additional rods 17 similar in all respects to the rods 14, are inserted through the lower portions of the head blocks and the partitions and when the nuts on the ends of the several rods are turned home the ends of the tank, the head blocks, and the partitions will be firmly clamped together so that water-tight 85 joints will be effected. It will be readily noted upon reference to Fig. 2 that the front and rear walls of the hopper at the lower end thereof fit against the upper ends of the head blocks and the projecting tongues of 90 the partitions and against the rear wall of the tank, respectively, and to secure the hopper in place so that a water-tight joint around the lower end of the same will be effected, I provide the rod 18 which is inserted through the end walls of the tank and so located that it bears against the front sides of the head blocks and forces them against the hopper, winged nuts 19 being fitted upon the threaded ends of the rod 105 110

and turned home against the walls of the tank to firmly secure the parts. The lower portions of the head blocks are enlarged and provided with curved surfaces, as shown 5 at 20, whereby the material passing through the amalgamating chamber 5 will be deflected toward and held against the amalgamating plate and the amalgamation of the valuable particles with the said plate will 10 be facilitated. In the lower ends of the head blocks and the partitions, I provide alined slots or notches 21 and 22 which accommodate a dam or bridge plate 23 extending longitudinally of the amalgamating chamber 15 and through the said slots. Near the ends of this dam or bridge plate and near the upper edge of the same, I provide openings 24 which are engaged by the lower hooked ends 25 of suspending rods 26 which extend up through the end head blocks and are equipped at their upper ends with winged nuts 27 adapted to be turned home against a bar 28 which extends across and rests upon the upper extremities of all the head blocks 20 and the partitions. It will be readily understood that by adjusting the nuts 27, the lower edge of the plate 23 may be set closer to or farther from the bottom of the amalgamating chamber so that the flow of material 25 through the amalgamating chamber and under the dam may be regulated. It will, of course, be understood that mercury, indicated at 29, is placed in the amalgamating chamber and settles at the bottom of the same so that the lower portion of the plate 23 will be submerged and the mercury forms a seal which tends to prevent flow of material under the dam.

The construction and arrangement of the 40 several parts of the apparatus being thus made known, it is thought the operation will be readily understood. The concentrates or material to be treated is fed through the hopper and descends at once to the several 45 compartments of the amalgamating chamber and is deflected toward the rear wall thereof by the head blocks. At the beginning of the operation, the weight of the mercury will be greater than the weight of the water and the 50 concentrates suspended therein so that the material will be held back until its weight exceeds the weight of the mercury, whereupon the mercury will be forced toward the front of the chamber up against the amalgamating plate and the water and concentrates will tend to flow under the dam. The 55 result of this movement will be to set up a whirling or eddying motion in the mercury and the water, so that the water and concentrates will be commingled with the mercury and the increasing weight of the concentrates as the feeding continues will force the same through the mercury and spread the mercury on the amalgamating plate so 60 that the plate will be kept moist with mer-

cury automatically. The whirling, eddying motion will carry the valuable heavier particles against and amalgamate them with the amalgamating plate 7 while the lighter particles and the impurities will be washed 70 from the mercury by the water and will pass over the bridge 7 into the receptacle 6, the water eventually overflowing from said receptacle while any valuable particles which may have been retained therein will 75 be deposited at the bottom of the receptacle as a sediment. As the valuable particles are removed from the water, the weight of the water and the concentrates at the rear of the head blocks will decrease and such 80 decrease in weight will permit the mercury to return to its initial normal position which it will retain until the weight of the water and the concentrates again exceeds the weight of the mercury, whereupon the mercury will be again forced to the front of the amalgamating chamber. This alternating movement or circulation will be kept up continuously until the supply of concentrates has been exhausted or until all of the 85 mercury has been amalgamated with the valuable particles and the amalgamating plate whereupon the amalgamating plate may be removed and the valuable matter recovered in the usual manner.

It will be readily noted that my apparatus operates automatically as long as material is fed into the hopper and requires no attention upon the part of the operator during the amalgamating process. The valuable 100 particles contained in the water or semi-liquid material will be rapidly and thoroughly separated from the material and the impurities which may be present in the mercury will be washed therefrom by the constantly flowing water so that the ultimate product will be practically free of all impurities. The apparatus is very simple in construction and may be rapidly and economically set up and operated.

Having thus described the invention, what is claimed as new is:

1. An amalgamator comprising end plates, a bottom plate disposed between the end plates and forming a rear amalgamating chamber, a front receptacle and a bridge connecting the chamber and receptacle, clamping rods inserted through the end plates below the bottom plate and securing the parts firmly together, a removable amalgamating plate forming a lining for the amalgamating chamber and extending over the bridge at the front of the same, means for delivering concentrates at the top of the amalgamating chamber and at the rear of the same, and means for directing the concentrates onto the amalgamating plate.

2. An amalgamator comprising end plates, an amalgamating chamber secured between the end plates, partitions extending across

the amalgamating chamber and provided with shoulders at their upper ends in their rear portions, head blocks disposed within the amalgamating chamber between the partitions, a hopper resting upon the shoulders of the partitions between the upper ends of the head blocks and the rear wall of the amalgamating chamber, and means for securing the head blocks, the partitions, and the hopper together.

3. An amalgamator comprising an amalgamating chamber, partitions extending across the said chamber and having upwardly projecting tongues intermediate 15 their front and rear edges, head blocks disposed within the amalgamating chamber between the partitions and having the front and rear faces of their upper portions flush with the edges of the tongues in the partitions, a hopper having its lower end resting

on the tops of the partitions in rear of said tongues, means for securing the partitions and the head blocks together, and means for clamping the hopper between the head blocks and the rear wall of the amalgamating chamber. 25

4. An amalgamator comprising an amalgamating chamber, partitions extending across said chamber and having slots in their lower ends, head blocks disposed within the 30 chamber between the partitions and having slots in their lower ends alining with the slots in the partitions, a dam extending longitudinally of the amalgamating chamber through the slots in the head blocks 35 and the partitions, and suspension devices carrying said dam and adjustably fitted through some of the head blocks.

In testimony whereof I affix my signature.
FRANCIS M. LEWIS. [L. s.]
